UNITED STATES PATENT OFFICE

HERBERT J. GRAHAM, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA

LAMP

Application filed April 25, 1929. Serial No. 357,906.

This invention relates to electric lamps and more particularly to electrically operated flood lights, search lights, head lights and the like, which are intended for projection of light over comparatively great distances or areas.

It is among the primary objects of this invention to provide in lights of the character to which the invention appertains means for adjusting or regulating the focal relation between the source of illumination and a reflector operatively associated therewith, said means being operable from a point located exteriorly of the lamp body or casing within which both the light source and the reflector are housed.

Auxiliary to the aforementioned object is the provision of a mechanism by means of which an electric lamp socket and the lamp received therein may be shifted radially of the lamp body or casing and along the vertical diametral line thereof, or adjusted such that the longitudinal axis thereof makes a predetermined angle with the vertical, or moved laterally to either side of said vertical diametral line, the several adjustments being performed individually or conjointly to obtain that exact focal relation between the lamp and its reflector as may be desired.

Heretofore it has been a more or less serious problem to protect and preserve the reflecting surface of the reflector from the deleterious effects of the heat produced by lamps of high wattage. It is accordingly a still further object of the invention to provide means for increasing the rate of radiation of the heat generated in the lamp body or casing to thereby obtain a lowered temperature therewithin, in consequence of which the life and effectiveness of the reflecting medium of the reflector is considerably increased. In the attainment of this object, the lamp body or casing is provided with a radially projecting enclosure for the lamp socket and the focusing mechanism hereinbefore referred to, said enclosure being provided in its external surface with a plurality of radially extending annular fins which serve as means for quickly carrying away from the interior of the lamp body the heat

which may be generated in the base or neck of the incandescent light bulb.

Other objects of the invention will appear more fully hereinafter.

The invention consists substantially in the combination, construction, location and relative arrangement of parts, all as will appear more fully hereinafter, as shown in the accompanying drawings and as finally pointed out in the appended claims.

In the accompanying drawings, which illustrate preferred embodiments of the present invention:

Figure 1 is a vertical sectional view through the top portion of a light embodying the features of this invention, said view being taken on the line 1—1 of Figure 3;

Figure 2 is a similar view but at right angles to that of Figure 1, this view being taken on the line 2—2 of Figure 3;

Figure 3 is a top plan view of the focusing mechanism with the cover therefor removed;

Figure 4 is a vertical section taken on the line 4—4 of Figure 1;

Figure 5 is a vertical sectional view showing a modified form of focusing mechanism constructed in accordance with the present invention as embodied in the bottom of a light; and

Figure 6 is a vertical sectional view taken at right angles to that shown in Figure 5.

Referring now to the drawings and more particularly to Figures 1 and 2, it will be observed that the invention has been embodied in a flood light or the like having a substantially drum-shaped lamp body 10 upon the rear wall 11 of which is suitably positioned a reflector 12. The frontal opening of the lamp body is closed by a front door closure (not shown) to provide a normally sealed housing for the reflector and the source of light 13.

Projecting radially upwardly from the annular wall 14 of the lamp body 10 and communicating with the interior of said body through an opening 15 provided in said wall is a substantially cylindrical body 16 having an aperture 17 in one side thereof. The bottom edge of the cylindrical body 16 fits snugly within and is permanently secured to the

peripheral edge of the opening 15, preferably by means of an annular welded joint 18. Integrally formed on the internal surface of the cylindrical body 16 and below the upper edge thereof is an annular flange 19, circumferentially spaced portions of which project inwardly and in the plane of said flange to provide a series of shelves 20, 21 and 22. As appears most clearly in Figure 3, the shelves 21 and 22 are diametrically opposed to the shelf 20 and are spaced laterally apart to provide a substantially T-shaped slot or opening 23 in the top of the cylindrical body 16.

Superposed upon the flange 19 and secured thereto, preferably by rivets 24, is a plate member 25 of a form corresponding to that of said flange 19, this plate member 25 being also provided with a central T-shaped opening adapted for registry with that which is defined by the inner marginal edges of the flange 19. Integrally formed in that portion of the plate member 25 which overlies the shelf 20 is an upwardly projecting and inwardly inclined boss 26, both the boss 26 and the shelf 20 being commonly provided with a continuous internally threaded bore 27. Integrally formed in each of those portions of the plate member 25 which overlie the shelves 21 and 22 of the flange 19 is an upstanding journal member 28, the two journal members so provided being spaced laterally apart and disposed in parallel relation. The journal members 28 are respectively provided in the upper portions thereof with horizontally aligned apertures 29 through which is projected a threaded bearing screw 30. This screw is provided at one end with a kerfed operating head 31 and at its opposite end with an annular shoulder 32, said head and shoulder serving to prevent longitudinal displacement of the screw but permitting rotation thereof between the journal members 28.

Extending transversely across the head of the T-shaped opening provided in the superimposed flange 19 and plate member 25 is a member 33, one end of which terminates between the journal members 28 and is provided with a horizontally extending internally threaded bore 34 for threaded engagement with the bearing screw 30 such that the latter affords a pivotal support for the member 33. The free end of this member 33, which is arranged to terminate just above the inner edge of the inclined boss 26, is of substantially cylindrical cross-section and is provided with opposed lateral extensions 35 continuous therewith and of the same section. Extending vertically through the central portion of the member 33 is an internally threaded bore 36 within which is threadedly received a screw 37, the function of which will be explained in greater detail herein-after.

Operatively associated with the free end of

the member 33 is the adjusting nut 38, the latter being best shown in Figure 1. This nut 38 is provided with a suitably kerfed head 39 and a threaded shank 40 arranged to be threadedly received within the inclined bore 27 formed in the boss 26. As appears most clearly in Figure 1, the head 39 of the adjusting stud is provided with an annular groove or recess 41 within which is snugly received the free end of the member 33. By virtue of the fact that said free end is in the form of a laterally extending flange of cylindrical cross-section, there is provided an articulation between the member 33 and the adjusting stud 38 of a character which permits the former to be shifted laterally with respect to the latter without the joint being broken.

From the foregoing description of the several parts of this invention so far mentioned it will be apparent that by rotation of the bearing screw 30 in one direction or another the member 33 may be shifted bodily in a direction paralleling the longitudinal axis of the bearing screw, this movement of the member 33 being permitted without disruption of the articulated connection between the member 33 and the adjusting stud 38. The extent of this lateral movement of the member 33 is limited by the journal members 28. On the other hand, angular adjustment of the member 33 about the bearing screw 30 is obtained by rotation of the adjusting stud 38 in one direction or another. Thus, upon rotation of the stud in counter-clockwise direction the free end of the member 33 will be lifted upwardly while rotation thereof in clockwise direction will cause said end to be depressed. While in Figures 1 and 2 the central screw 37 (that which is carried by the member 33) is shown with its axis extending vertically and disposed in a plane passing through the axis of the adjusting stud 38 and normal to the bearing screw 30, by virtue of the two adjustments just described the central screw 37 may be shifted to either side of said plane at the same time that it may be inclined with respect to the vertical.

As best appears in Figures 2 and 3, it will be observed that the member 33 is provided intermediate the ends thereof with a cross-head comprising a pair of oppositely extending projections 42—42 each of which is provided with an opening 43. These openings 43 are arranged to either side of the central internally threaded bore 36, the axes of said openings and said bore being disposed in a common plane. As has already been pointed out, a screw 37 is threadedly received within the central bore 36, the upper end of this screw being kerfed, as at 44, while the lower end is provided with an annular shoulder 45. Respectively arranged for vertical movement through the laterally disposed openings 43 of the member 33 are a pair of

guide studs or stems 46, the upper ends of which are provided with pins or other suitable means 47 for limiting the downward movement of said studs within their respective openings 43.

The lamp socket 47' is supported from the member 33 through the intervention of a pair of superposed strap members 48—49 between which the shoulder 45 at the bottom end of the central screw 37 is received, it being observed that this screw passes upwardly and freely through an opening 50 provided in the upper strap member 48 to thereby permit rotation of said screw independently of said strap members. Opposite ends of the strap members 48—49 are commonly apertured, as at 51, for respectively receiving the reduced lower ends of the guide studs 46, which latter are in turn suitably secured to the socket 47' by screws 52. By virtue of the arrangement just described for supporting the lamp socket, it will be readily seen that while said socket is axially movable toward and away from the member 33 it is precluded from rotating relatively with respect to said member, the said axial adjustment being effected by rotating the screw 37 in one direction or another.

From the foregoing it will be observed that a substantially universal adjustment may be had of the incandescent bulb 13 which is carried by the socket 47', the latter being shiftable laterally in a direction paralleling the bearing screw 30, or adjustable angularly about the axis of said bearing screw, or movable toward or away from the member 33. Obviously, these adjustments, which are respectively effected by the lateral adjusting screw 30, the adjusting stud 38 or the central adjusting screw 37, may be performed individually or conjointly to obtain the exact focal relation between the light source 13 and the reflector 12 as may be desired. Inasmuch as each adjustment is obtained through the action of a screw no additional or auxiliary locking means need be employed for maintaining the bulb in the adjusted position. Furthermore, in each instance the adjustment may be readily effected by means of one tool, such as a screw driver, which is engaged in the slot commonly provided in the head of each adjusting element.

The focusing mechanism as just described is protected from the weather by a dome-like cap or cover 53 which fits over the upper edge 55 of the cylindrical body 16 within which the mechanism is housed. An annular gasket 54 suitably retained in position immediately within the peripheral edge of the cap 53 serves as a hermetic seal between said cap and the upper edge of the cylindrical body 16. The cap 53 is retained in position and against displacement by a bail 55, preferably of spring wire, the trunnions 56 of which are pivotally received within diametrically opposed socketed bosses 57 which project radially from the

cylindrical body 16. An offset portion 58 in the transverse portion of the bail yieldingly engages a central depression 59 in the cap 53, the pressure of this bail upon the cap being sufficient to compress the gasket 54 so as to form a fluid tight seal between the cap and its support. The cap may be loosely connected to the body 16 by means of a flexible chain 60 for preventing its accidental loss or misplacement.

In light projectors of the type shown in Figures 1 and 2, the incandescent bulb used is of such capacity as usually necessitates some means for carrying the generated heat away from the interior of the lamp body. Generally this has been accomplished by ventilating the lamp body at the risk of leakage or entrance of dust, moisture and the like into the interior thereof. To prevent this entrance of deleterious elements and yet provide for an ample radiation of heat the cylindrical body 16 enclosing the socket 47' is provided on its external surface with a plurality of annular heat radiating fins 61. Inasmuch as by far the greatest amount of heat is concentrated in the immediate vicinity of the neck and base of the incandescent bulb these fins 61, which thus embrace the vicinity of greatest heat concentration, serve as efficient means for quickly conducting the generated heat away from the interior of the lamp body. As clearly appears in Figure 1, the cylindrical body 16 is provided with a conductive type terminal 62 through which suitable conducting wires (not shown) are connected to the lamp socket 47. The wires leading from said socket pass through the opening 17 in the side of the body 16 for connection to a suitable terminal block (not shown) within the terminal 62.

Figures 5 and 6 show a somewhat modified arrangement of focusing mechanism as employed at the bottom instead of at the top of the lamp body or casing 10. As in the former instance this lamp body encloses a reflector 12 and a source of light 63, it being observed that the latter is provided with a much shorter base than is the bulb shown in Figure 1. Provided in the bottom of the annular wall 14 of the lamp body 10 is an opening 64 over which is directly secured a plate member 65, the latter being substantially similar to the plate member 25 herefore described in connection with Figures 1 to 4. The plate member 65 is integrally secured to the peripheral edge of the opening 64, preferably by an annular welded joint 66. Operatively associated with the plate 65 are the member 67, the lateral adjusting screw 68, and the adjusting stud 69, all of which are substantially identical to the corresponding parts of the top focusing arrangement already described. The mechanism for adjusting the bulb 63 toward or away from the member 67, i. e., radially of the center 130

of the lamp body, differs somewhat from the corresponding mechanism of Figures 1 to 4.

As appears quite clearly in Figures 5 and 6 the member 67 has threadedly secured there-
5 to a hollow sleeve 70, the free end of which is threaded, as at 71, to receive a cross-head 72. The opposite ends of this cross-head 72 are apertured, as at 73, to slidably receive
10 guide studs or stems 74, which latter are se-
cured, by means of screws 75 and through the intervention of the superposed strap mem-
bers 76—77, to the base of the lamp socket 78. Pins 79 respectively provided in the lower
15 ends of the guide studs 74 limit the inward movement thereof through the cross-head 72.

The hollow sleeve 70 is internally threaded, as at 80, throughout the upper portion there-
of for threadedly receiving an operating stem
20 81, the lower end of which projects free of
said sleeve and is provided with a knurled operating knob 82. The unthreaded portion of the stem 81 is of reduced diameter and forms with the threaded portion thereof a shoulder 83 which coacts with the internal
25 shoulder 84 of the sleeve 70 to limit the out-
ward movement of the stem 81. The upper or inner end of the operating stem is pro-
vided with a head 85 received between the strap members 76—77, the arrangement be-
30 ing such as to permit rotation of the operat-
ing stem independently of the cross-head 72
and accordingly the lamp socket 78. As in
the case of the upper focusing mechanism the bottom mechanism is also enclosed by
35 a removable dome-like cap 86 which is re-
tained in place by a spring wire bail 87.

It will be observed that in the modified arrangement, as shown in Figures 5 and 6, the operating screw is of considerably greater length than the corresponding screw of Figures 1 and 2, thus making it possible to position a bulb of smaller capacity or different type centrally of the reflector without radically changing the focusing mechanism
40 as a whole and without necessitating access to the interior of the lamp casing to effect the proper focal adjustment of the light source relative to its reflector. In each of the de-
scribed arrangements the number of possible
45 adjustments for insuring proper focal relation and the character thereof are the same, as is the manner of effecting such adjust-
ments. It will be understood, of course, that various changes may be made from time to
50 time without departing from the general spirit or principles of the invention, as indicated by the appended claims.

What is claimed as new and useful is:

1. In a light projecting device, in combi-
60 nation, a hollow casing having an opening therein, an apertured plate positioned over said opening, an axially immovable bearing screw journaled upon one side of said plate, a member extending across said plate aper-
65 ture having one end thereof pivotally mount-

ed upon said screw, the free end of said member being provided with an elongated exten-
sion paralleling said screw, said screw being adapted for rotation whereby to shift said member in the direction of its pivotal axis, an axially movable stud received in said
70 plate and slidably engaging the elongated extension of said member to adjust the latter angularly about said axis, and a lamp-sup-
porting screw movable axially through said member and projecting interiorly of said casing through said opening.

2. In a light projecting device, in combi-
nation, a hollow casing having an opening
80 communicating with the interior thereof, a lateral screw arranged at one edge of said opening, an axially adjustable stud mounted at the opposite edge of said opening, said stud being capable solely of an axial move-
ment, a member having one end journaled
85 upon said screw with the opposite end there-
of engaging said stud, cooperating means in
said stud and member for permitting the lat-
ter to be shifted in a direction paralleling
90 said screw without effecting its disengage-
ment from said stud, and an axially adjust-
able lamp-supporting stem carried by said
member and projecting interiorly of said
95 casing through said opening and along a line disposed between said lateral screw and said stud.

3. In a light projecting device, a focusing mechanism including a rotatably mounted bearing screw, a member pivotally secured at one end to said screw with capacity for move-
100 ment in the direction of its pivotal axis upon rotation of said screw, an axially movable stud capable only of rectilinear movement operatively associated with the free end of said member, means affording an articulated connection between the free end of said member and said stud for precluding disengage-
105 ment of said member from said stud upon movement of the former in the aforesaid di-
rection, said stud being operative to adjust
110 said member angularly about said pivotal axis, and lamp supporting means arranged for axial movement through said member.

4. In a light projecting device, in combina-
115 tion, a hollow casing having an opening there-
in, an apertured plate positioned over said opening, a bearing screw journaled upon one side of said plate, a member extending across said plate aperture having one end thereof pivotally mounted upon said screw, said screw being adapted for rotation whereby to shift said member in the direction of its pivotal axis, a headed stud threadedly re-
120 ceived in said plate, the head of said stud being provided with an angular groove within which is tangentially received the op-
posite end of said member, and a lamp socket supported by said member.

5. In a light projecting device, a focusing mechanism including a rotatably mounted
130

bearing screw, a member pivotally secured at one end to said screw with capacity for movement in the direction of its pivotal axis upon rotation of said screw, an axially movable 5 stud having a groove and tongue connection with the free end of said member, means for precluding disengagement of said member from said stud upon movement of the former in the aforesaid direction, said stud being 10 operative to adjust said member angularly about said pivotal axis, and a lamp socket carried by said member.

6. In a light projecting device, in combination, a focusing mechanism including a rotatably mounted bearing screw, a member arranged with said screw projecting through one end thereof, the opposite end of said member being provided with an elongated extension paralleling said screw, axially adjustable means having an annular groove within which said extension is tangentially received, and a lamp socket carried by said member, said axially movable means being operative to effect angular displacement of 20 said member relatively to said screw and said screw being operative to effect a tangential movement of said member relatively to said axially adjustable means.

7. In a light projecting device, a focusing mechanism including a member arranged for angular adjustment about a fixed axis, said member being provided at one end thereof with a pair of opposed lateral extensions to provide conjointly with said end of the member a transversely extending head, and a rectilinearly adjustable element intersecting the plane of said member for effecting said angular adjustment thereof, said element having a groove within which said head is adapted to be received for transverse movement in a 35 direction paralleling said axis.

8. In a light projecting device, in combination, a focusing mechanism including a member arranged for angular adjustment about a fixed axis, a stud capable solely of a rectilinear movement in the direction of its axis for effecting said angular adjustment of said member, means for axially adjusting said member along said fixed axis, an articulated 45 connection between the free end of said member and said stud including interengaging tongue and groove elements for effectually precluding disengagement of said member from said stud during the angular and axial 50 adjustments of said member, and a lamp socket carried by said member.

In testimony whereof, I have hereunto affixed my signature.

HERBERT J. GRAHAM.
